DESIGN FOR A BOTTLE

Herbert Rubin, Brooklyn, N. Y.

Application March 1, 1939, Serial No. 83,276

Term of patent 7 years

To all whom it may concern:

Be it known that I, Herbert Rubin, a citizen of the United States, residing at Brooklyn, in the county of Kings and State of New York, have invented a new, original, and ornamental Design for a Bottle, of which the following is a specification, reference being had to the accompanying drawing, forming part thereof.

Figure 1 is a front view, Figure 2 is a side view, and Figure 3 is a perspective view of a bottle, showing my new design.

The design is characterized by a bottle of the particular contour shown, including opposed,

elliptical frusto-conical top and bottom portions of substantially equal dimensions separated by a relatively narrow, plain band at the middle section of the bottle, with the upper and lower frusto-conical portions having flutings extending the entire distance from said band to the shoulder and bottom, respectively, of the bottle, in the manner illustrated.

I claim:

The ornamental design for a bottle, substantially as shown and described.

HERBERT RUBIN,
